UNITED STATES PATENT OFFICE.

CLARENCE D. PLATT, OF BRIDGEPORT, CONNECTICUT.

HICKEY.

1,093,007.

Specification of Letters Patent. Patented Apr. 14, 1914.

Application filed January 4, 1913. Serial No. 740,111.

To all whom it may concern:

Be it known that I, CLARENCE D. PLATT, a citizen of the United States, residing at Bridgeport, county of Fairfield, State of Connecticut, have invented an Improvement in Hickeys, of which the following is a specification.

This invention relates to electrical fixtures and has for its object to provide a hickey or connection between an electrical fixture and its support, which will permit the parts to be assembled without danger of twisting the wires or of injuring them in any way. In other words, I provide adequate protection for the fixture wires under all the conditions of use. It is of course well understood that devices of this class, whether the threads are male or female, are threaded or tapped with pipe taps or dies and are tapered for the purpose of making tight joints without shoulders and that the various parts which make up a complete fixture are frequently furnished by different manufacturers. As no standard has been established in the manufacture of these parts they cannot be depended upon to thread together as accurately as is desirable or necessary.

My present invention enables me to insure perfectly firm and rigid connections and full protection against twisting of the wires or any injury thereto in attaching any ordinary fixture to any ordinary support. This I accomplish by providing a hickey which may have two male or two female threads or one male thread and one female thread, but which shall be provided in any event with shoulders, which positively limit the movement of either the fixture connection or the support connection in engaging the hickey, and with a slot into which the fixture wires are passed and which shall extend below the upper shoulder far enough to receive the wires and to protect them against any abrasion that might injure the insulating covers.

With these and other objects in view I have devised the novel hickey which I will now describe, referring to the accompanying drawing forming a part of this specification and using reference characters to indicate the several parts.

Figure 1 is a view partly in elevation and partly in section illustrating a form of hickey, having two female threads, assem-

bled with fixture and support connections as in use; Fig. 2 a plan view on an enlarged scale of that form of hickey detached; Fig. 3 a longitudinal section corresponding therewith showing the support and fixture connections screwed down into engagement with the corresponding shoulders; Fig. 4 a view partly in elevation and partly in section illustrating a form of my novel hickey provided with two male threads, and showing the support and fixture connections screwed down into engagement with the shoulders; and Figs. 5 and 6 are sectional views illustrating forms of my novel hickey each provided with one male and one female thread, and the corresponding shoulders.

10 denotes the support connection which is provided with an insulating joint 11. In the form illustrated in Fig. 1 the support connection is the form commonly known as "crow foot", and the insulating joint is provided with a male thread 29, see Fig. 3.

12 denotes the fixture connection which is simply a tube provided with a male thread 30.

13 denotes the main wires and 14 the fixture wires. These wires are soldered or otherwise secured together to complete the installation and the parts are ordinarily covered by a ceiling canopy 15.

16 denotes the body of my novel hickey which is provided with an opening 28 through it, through which the fixture wires pass, and with threads for engagement with the connections. In the form illustrated in Figs. 1, 2 and 3 the body is provided with two female threads 20, the upper thread terminating in an internal shoulder 17 and the lower thread in an internal shoulder 18. Extending inward from one end of the body in all the forms is a slot 19, in which the fixture wires are placed in assembling, as shown in Fig. 1. This slot extends past the corresponding shoulder so as to provide ample space for the wires and prevent pinching.

The hickey may, of course be used either end upward but is ordinarily used with the slotted end upward as shown, and for convenience in description I will refer to the shoulder in the slotted end as the upper shoulder and the other shoulder as the lower shoulder.

It is an essential feature of construction in all of the forms that the slot extend past the upper shoulder far enough to provide

ample space to receive the fixture wires so that when the hickey is turned on to the support connection there can be no possibility of the end of the connection coming 5 into contact with the wires to abrade them and injure the insulating covers. By placing the wires in the slot it is also insured that the wires will not become twisted in attaching the hickey and fixture connection 10 to the support connection. The two shoulders are vitally important features of construction in that they prevent the possibility of either connection being turned into the hickey far enough to injure the wires under 15 any condition of use.

In the form illustrated in Fig. 4, the body is provided with two hubs, each of which is provided with a male thread 21. In this form the slot extends entirely through the 20 upper hub and well down into the body of the hickey, as in the other form. The support connection, indicated by 22, is provided with a female thread 23 which is engaged by the male thread of the upper hub and the 25 fixture connection indicated by 26 is provided with a female thread 27 which is engaged by the male thread of the lower hub. 24 denotes the upper shoulder and 25 the lower shoulder, both of which are external 30 to the body of the hickey and are engaged by the ends of the fixture and support connections, as in the other form. It is of course not essential that the ends of the 35 connections engage the shoulders in either of the forms. They will not of course engage if the connections are shorter than the threads of the hickey. By providing the shoulders however I insure that if the threaded ends of the connections happen to 40 be longer than the threads of the hickey the movement of the connections in engaging the hickey will be stopped by the shoulders

and no possible injury can result to the wires.

In the form illustrated in Fig. 5, the upper end of the body is provided with a hub having a male thread 21 and the lower end is provided with a female thread 20. The support connection is provided with a female thread 23 as in Fig. 4 and the fixture connection with a male thread 30 as in Fig. 3. The upper end is provided with an external upper shoulder 24 and the lower end with an internal lower shoulder 18. The slot extends down well past the upper shoulder as 55 in the other forms.

The form illustrated in Fig. 6 is the reverse of that in Fig. 5. The upper end of the body is provided with a female thread 20 and the lower end with a hub having a male thread 21. In this form, the support connection is provided with a male thread 29 as in Fig. 3 and the fixture connection with a female thread 27 as in Fig. 4. The upper end of the body is provided with an 60 internal upper shoulder 17 and the lower end with an external lower shoulder 25. The slot extends well down below the upper shoulder as in the other forms.

Having thus described my invention I 70 claim:

A hickey comprising a tubular body provided with a central longitudinal opening therethrough and having female threads at each end, shoulders at the termination of 75 said threads, for the purpose set forth and a longitudinal slot extending from one end to a point between the shoulders.

In testimony whereof I affix my signature in presence of two witnesses.

CLARENCE D. PLATT.
